UNITED STATES PATENT OFFICE.

THOMAS J. DIXON, OF MADISON, WISCONSIN.

PEN OR PENCIL HOLDING DEVICE.

1,382,487.

Specification of Letters Patent. Patented June 21, 1921.

Application filed March 10, 1921. Serial No. 451,407.

To all whom it may concern:

Be it known that I, THOMAS J. DIXON, a citizen of the United States, residing at Madison, in the county of Dane and State 5 of Wisconsin, have invented a new and Improved Pen or Pencil Holding Device, of which the following is a specification.

My invention has reference to improvements in that class of pen or pencil holding 10 devices adapted to hold the writing element on one of the fingers of the hand and in such manner that the writing element is handy when it is to be used, and is out of the way when not in use and does not interfere with the hand or fingers for other 15 than writing uses.

Primarily, my invention has for its object to provide an improved device of the character stated, very simple and inexpensive 20 in construction, that can be readily placed on any of the fingers of either hand to hold the pen or pencil in a way to relieve the fingers of the steady strain caused by holding the pen or pencil too tightly while 25 using it, and which prevents displacement and loss of the writing element and allows for the quick insertion or removal of such element from the holder, as desired.

Another and essential object of my invention 30 is to provide a device for the purpose described that is shaped up from a single piece of resilient material in the form of an open band ring having sufficient resiliency whereby to fit and hold tightly on any finger 35 of the hand to which it may be applied and which has an integral spring member with which the pencil or pen holder slidably engages and which clasps the said writing element under sufficient tension to prevent 40 its becoming easily disconnected from the holder.

With other objects in view that will hereinafter be apparent my invention embodies, 45 in a pen or pencil holding device of the kind stated, the peculiar construction and arrangement of the parts thereof as will be fully explained in the following detailed description, specifically pointed out in the appended claims and illustrated in the accompanying drawing, in which:

Figure 1 is a perspective view showing the embodiment of my invention as in use, the dotted lines indicating the device and the pencil when adjusted to a position out 50 of use.

Figs. 2 and 3 are perspective views of preferred forms of my device.

In the practical development of my invention, the device consists of a ring shaped flat band of suitable flexible or resilient material, which band is preferably a split ring 60 so that it may be readily placed and by its resiliency held, upon any of the fingers of either hand.

In the preferred form of my invention, as 65 shown in Figs. 2 and 3, the flat band ring 1 is split and at one end has a keeper 2 that is disposed crosswise of the band and into which the pen or pencil holder is received when the device is applied for use. 70

The keeper 2, in the form of my invention shown in Fig. 2, is in the nature of a spiral coil that is bent up from a strip of metal 10 which is left on one of the split ends of the band as the latter is punched out, the said 75 strip, in practice, being bent around, in any suitable manner, to produce the laterally extended coil shaped keeper 2, the latter, as well as all of the keepers 2 in the several modified forms of my invention to be presently explained, being disposed at an incline 80 to the cross section of the ring to provide for the required inclination of the pen or pencil holder when using the same as is indicated in Fig. 1. 85

In Fig. 3, it is shown that instead of forming the coil shaped keeper 2 from an extension at one end of the pen, as in Fig. 2, the band is cut lengthwise, the cut extending some distance around the band and ending near one of its ends. 90

The strip 20, formed by making the cut in the band stated, is pulled outwardly toward the band end and then is manipulated, in any suitable way, to form the coil 20 95 which is bent and extended laterally of the ring band in position for slidably receiving therethrough the pen or pencil holder.

From the foregoing description, taken in connection with the drawing, the complete 100 construction, the manner of its use and the advantages of my invention will be readily apparent to those familiar with the use of devices of this kind, it being obvious that in all of the different forms of my invention, 105 as shown, the ring band, when the pencil is to be held on the hand, but out of position for use, need only be turned around the finger to bring the keeper 2 in such position that the pen or pencil is held along the back 110

of the finger and out of the way of using the said finger for other purposes, as is indicated in dotted lines in Fig. 1.

What I claim is:

- 5 1. A device of the character stated comprising a ring band, provided with a strip extending in the direction of its length adapted for being shaped into a coil and projected laterally of the band for receiving and sustaining a pen or pencil.
- 10 2. A device of the character stated comprising a ring band slitted in the direction of its length whereby to form an elongated

strip, the said strip being bent outwardly from the ring band and coiled to constitute 15 a keeper, the coil or keeper being projected laterally to one side of the ring.

3. As a new article, a finger operated pen or pencil holder consisting of a split band ring, the band having a strip bendable 20 therefrom, the said strip being coiled to form a loop for receiving a pen or pencil and extended laterally from the band and diagonally with respect to the said ring band.

THOMAS J. DIXON.
